UNITED STATES PATENT OFFICE.

LAZURE L. GOODMAN, OF INDIANAPOLIS, INDIANA, ASSIGNOR TO REAL SILK HOSIERY MILLS, OF INDIANAPOLIS, INDIANA, A CORPORATION OF INDIANA.

SAMPLE CASE, CONTAINER, AND DISPLAY STRUCTURE.

Application filed October 6, 1923. Serial No. 666,947.

To all whom it may concern:

Be it known that I, LAZURE L. GOODMAN, a citizen of the United States, residing at Indianapolis, in the county of Marion and

5 State of Indiana, have invented certain new and useful Improvements in Sample Case, Container, and Display Structures, of which the following is a specification, reference being had therein to the accompanying drawing.

10 This invention primarily relates to a combined sample case, container, and display structure; it has especial reference to that class known as sample cases for receiving and displaying articles of merchandise; and it is particularly useful in the so-called systems of house-to-house sale of such articles.

The primary object of the invention is to 20 provide a structure which is neat in appearance, comparatively inexpensive to manufacture, and convenient to handle at all times, and whereby merchandise-samples may readily be inserted and held in a flat and unwrinkled condition, whether the case is open or closed.

Subsidiary objects and advantages of the structure will be self-evident from the following description:

30 In order that the invention may readily be understood, a preferred embodiment thereof is illustrated in the accompanying drawings, these being, however, merely illustrative. It is to be understood that the 35 embodiment herein revealed is susceptible of a wide range of modification and variation without departing from the salient features or underlying principles of the invention.

In these drawings:

40 Figure 1 is a view in elevation of the structure in open position and displaying articles of merchandise which, in this instance, are stockings and half-hose;

Fig. 2 is a similar view of the structure, 45 partly closed;

Fig. 3 is a similar view of the structure entirely closed;

Fig. 4 is a view in section on the line 4—4, 50 Fig. 3; and

Fig. 5 is a fragmentary view, in elevation, of the structure in open position.

In these drawings, the reference-character 1 designates, generally, a receptacle or case, constituting a combined sample-case, container, or display structure to receive

various articles of merchandise, such as hosiery.

The structure—being in this instance particularly adapted for holding and displaying hosiery—preferably comprises two 60 main sections or components 2 and 3, and a flap-section or component 4. The main sections or components are approximately of the same size, are each of flexible or unstiffened material, and are covered in any 65 appropriate manner and with any suitable material. The sections 2, 3 and 4 are, preferably and as shown, joined by a plurality of flexible or unstiffened parts or hinges 5 and 6, and whereby the sections are foldable 70 one upon the other. Associated with the hinge or bendable portion 6 are a plurality of fastening-devices 7 to subserve a function presently to be described.

Carried by the main-section 2 and the 75 flap-section 4 are coacting fastening-devices 8 and 9, respectively, and whereby the flap-section, when folded against the outer face of the main-section 2, may be fastened thereto and thereby hold the entire structure 80 securely closed.

Integral with, or otherwise attached to, the upper and lower portions of the main-section or component 3 are two article-carrying end-sections 10 and 11, respec- 85

These end-sections 10 and 11 are, preferably and as shown, connected to the section 3 by hinges or bendable portions 12 and 13, respectively, and these permit the end-sections to be folded into a normally closed position and against the inner face 3^a of the section 3 (as shown in Fig. 3), or to be opened out into a displaying position (as shown in Fig. 1).

The end-section 10 has connected to its outer-portion (as by a hinge or bendable portion 14) a flap 15 adapted, normally, to be folded against the inner face 10^a of that section and to be held in such folded position 100 by a suitable fastening-instrumentality, such as an elastic band or retaining-element 16. This flap, as influenced by said band, operates to hold in place the articles to be displayed which, in this instance, are stockings A and half-hose B. Similarly overlying the inner face 10^a of the end-section 10 is another retaining-element or elastic band 17 which operates to hold the articles A and B flat 105 against said face of the section and against 110

wrinkling and, particularly, when that section is, itself, being folded against the section 3 to fold the articles A and B between these two sections.

6 The end-section 11 also is, preferably and as shown, provided with a plurality of retaining-elements or elastic bands 18, which function to hold the foot-portions of the articles A (for instance) against the inner 10 face 11* of the section 11 in the same way and for the same purpose as the retaining-element 17 operates in conjunction with the section 10.

It will be understood from the foregoing 15 that the main sections 2 and 3, the flap-section 4, the end-sections 10 and 11, and the flap 15 may be regarded (for all practical purposes) as integral with each other and, in consequence, adapted to be folded into an 20 article-holding relation and, thus, into a very compact form, making the structure convenient to handle and carry and yet, when opened up, not of unwieldy or inconvenient dimensions. When being so opened 25 up, the articles contained therein are likewise automatically opened out into a flat condition for display purposes. The retaining-elements serve to hold the articles in proper position and condition, no matter in 30 what position the structure, itself, may be disposed.

It will be noted that when the end-sections 35 are folded into their closed position, a portion of one of them overlies a portion of the other.

Associated with the main sections, and secured at their hinge 6 by the fastener-devices 7, is a display-leaf 19, preferably of 40 stiff material and, in this instance, carrying color-indicating specimens 20 on one face, the opposite face being adapted, preferably, to engage the aforementioned overlapping portion of the end-section and thereby operate to hold the end-sections in closed position.

If desired, a plurality of leaves 21, of paper or like material and bearing illustrative and descriptive matter, may be secured, as by the fasteners 7, in association with the 50 main sections 2 and 3 and the display-leaf 19.

From the foregoing, it will be perceived that the structure herein disclosed includes a plurality of main sections joined by a bendable portion constituting a hinge, a flap-section also joined by a bendable section to one of the main sections, end-sections joined to one of the main sections by bendable portions, and a flap joined to one of the end sections by a bendable portion; all of these 60 sections being integral one with the other and foldable one upon another; and, in operative association therewith, interleaved display and illustrative elements, in the form of leaves that are detachably secured in the 65 structure and which, with the main sections

involving cover-members, constitute a book; all in combination with a display device comprising one of the main sections, the end-sections, the flap on one of these sections and the retaining-elements associated with the sections; and all presenting a structure which makes for convenience at all times, either when closed or open.

What I claim is:

1. A sample-case including an article-carrying main section, upper and lower article-carrying sections thereon, a second main section on one side of the first main section, article-holding leaves clamped between said main sections, a flap on the other side of the first-named section, and means for detachably securing the flap to the second main section.

2. A sample-case including an article-carrying main section, upper and lower article-carrying sections thereon and foldable thereover, a second main section on one side of the first main section, article-holding leaves clamped between said main sections, a flap on the other side of the first-named section, and means for detachably securing the flap to the second main section.

3. A combined sample-case and display-structure including a plurality of foldable main sections and a flap section, bendable connecting portions joining the sections, article-carrying sections on the upper and lower portions of one of the main sections and foldable against one face thereof, securing means for holding an article in secured position on the article-carrying sections and the main section which carries said article-carrying sections, and leaf-fastening means associated with the bendable portion which is located between two of the main sections.

4. A combined sample-case and display-structure including a plurality of foldable main sections and a flap-section, bendable connecting portions joining the sections, article-carrying sections on the upper and lower portions of one of the main sections and foldable against one face thereof, a flap joined to one of said article-carrying sections, securing means for holding the flap and an article in secured position on one of the article-carrying sections, and leaf-fastening means associated with the bendable portion which is located between two of the main sections.

5. A combined sample-case and display-structure including a plurality of foldable main sections and a flap-section, bendable connecting portions joining the sections, article-carrying sections on the upper and lower portions of one of the main sections and foldable against one face thereof, a flap joined to one of said article-carrying sections, securing means for holding the flap and an article in secured position on one

of the article-carrying sections, leaf-fastening means associated with the bendable portion between two of the main sections, and a display-leaf attached between the main sections by said fastening means.

6. A combined sample-case and display-structure including a plurality of foldable main sections and a flap-section, bendable connecting portions joining the sections, article-carrying sections on the upper and lower portions of one of the main sections and foldable against one face thereof, a flap joined to one of said article-carrying sections, securing means for holding the flap and an article in secured position on one of the article-carrying sections, leaf-fastening means associated with the bendable portion between two of the main sections, and a display-leaf attached between the main sections by said fastening means and overlying said article-carrying sections when in their closed positions.

7. A combined sample-case and display-structure including a plurality of foldable main book-sections, a flap section and integral bendable connecting portions joining the sections to constitute a book, in combination with article-carrying end sections on one of the main sections and a flap joined to and overlying one of said end sections, constituting with said main section a display structure, a display element interleaved between the main sections and, in the closed condition of the case, overlying the end sections, and fastening devices for securing said display element and for holding the book-sections in closed position.

In testimony whereof I affix my signature in presence of two witnesses.

LAZURE L. GOODMAN.
